GRADING MACHINE

James W. Johnston, Manchester, N. H., assignor
to North American Holding Corporation, Syra-
cuse, N. Y., a corporation of New York

Application August 14, 1936, Serial No. 96,072

11 Claims.

This invention relates to grading machines and particularly to machines for grading died out pieces of leather used in shoe making, and similar blanks, as by evening or marking the blanks, or both, in accordance with the thickness of the thinnest part thereof.

Although not limited thereto, the invention is particularly applicable to the well-known Nichols grading machines, and will be described in connection with a grading machine of the general type shown in the Nichols Patent No. 1,130,321.

An important object of the invention is to provide automatic mechanism for lifting the feed roller at the delivery end of the machine, which also constitutes the gauge roller in the case of a skiving (evening or fleshing) machine, thereby relieving the blank of the duty of lifting the feed roller as it has heretofore been obliged to do.

A further object of the invention is to provide a novel adjustable and non-rotatable blank support opposed to said roller.

In the accompanying drawings, which illustrate such parts of a Nichols grading machine as are necessary to an understanding of the present invention,

Fig. 1 is a side elevation partly in section of a grading machine particularly adapted to fleshing and embodying the invention;

Fig. 2 is a rear end elevation, partly broken away and partly in section, of the machine shown in Fig. 1;

Fig. 3 is a section on line 3—3 of Fig. 2;

Fig. 4 is a detail in plan view of the rigid supporting bar and associated parts hereinafter described; and

Fig. 5 is a sectional view, similar to Fig. 3, showing the application of the invention to an evening machine.

Referring first to Figs. 1 to 4, the machine has the usual measuring or detecting rolls 10 and 11 (Fig. 1) by which the blanks are fed forwardly one by one toward the marking wheel 12 and then to the skiving knife 13. During the passage of each blank between the measuring rolls 10 and 11 the thickness grade of the blank, which is established by the thickness of the thinnest part of the blank, or of that area of the blank which it is desired to measure, is detected, the lower roll 11 being caused to move up and down in response to variations in thickness of the blank. The lower roll 11 acts through the usual setting mechanism to adjust the transverse slide bar 14, to which are fixed the usual inclined or wedge-like abutments 52 (Fig. 2). The endwise adjustment of the slide bar 14 positions the abut-

ments so as to regulate the action of the skiving mechanism in accordance with the thickness grade of the blank, as determined by the detecting means (measuring rolls), and also acts through the usual mechanism to adjust the marking wheel 12 in accordance with said thickness grade.

The frame of the machine may have the usual table or shelf 18 on which the blanks are automatically and successively fed forward from the bottom of a stack S to the continuously rotating measuring rolls 10 and 11. The upper roll 10 is journaled in normally fixed bearing boxes and is continuously driven through gearing by the continuously rotating main drive shaft 15, 15 and the lower roll 11 is geared to and driven by the upper roll 10.

Each blank is fed forward by the rolls 10 and 11 into position between a presser bar 16 and a continuously traveling blank propelling carrier 20 or feed chain 17.

As the leading end of each blank emerges from between the measuring rolls 10 and 11 it operates the usual trip (not shown) to start the effective measuring action of the rolls 10 and 11 and preserve the measurement of the thinnest spot detected, by adjusting the slide bar 14 and consequently adjusting the abutments 52 crosswise of the machine and rotatively adjusting the marking wheel 12 in accordance with the measurement of the thinnest part of the blank as determined by the measuring rolls. As each blank is fed forward on shelf 18 it is fed under the usual gate 20, which is raised to admit the blank and then lowered to rest on top of the passing blank. When the rear or trailing end of the blank passes out from under the gate, the gate falls to the shelf 18 and acts through the usual mechanism to stop the measuring action and lock the usual setting devices in their final position of adjustment.

As the forward or advance end of the blank approaches the marking wheel it engages and depresses the usual trip 21 (Figs. 1 and 3) and acts through the usual mechanism to occasion a single complete revolution of the gear 22, which is normally at rest. The gear 22 acts through the usual train of gears 23 to impart a single complete revolution of the gear 24 fast on shaft 25. Shaft 25 carries the usual cam (not shown) and when thus rotated the cam raises and then releases the plunger 26 (Figs. 1 and 2) which carries the marking wheel 12 whereupon the plunger 26 and wheel 12 are forcibly thrown downwardly by the usual spring 27 to cause the

marking wheel to strike and mark the blank. From the marking wheel the blank is advanced to the skiving mechanism whose action is controlled by the position of the slide bar 14 and its abutments, which in turn are responsive to the detecting rolls.

As thus far described the construction and operation of the machine may be as usual in the well-known Nichols evening and grading machines.

The present invention has to do mainly with the skiving mechanism.

Heretofore the gauge roller above the skiving knife, which is also a feed roller, was required to be lifted by the leading edge of the advancing blank until it was arrested by the abutments, which had already been adjusted in accordance with the thickness measurement of the thinnest spot as found by the detecting rolls. This gauge and feed roller has usually been constructed as a comparatively heavy solid metal roller, and the weight of the roller, to which must be added the weight of the heavy gear 32 affixed thereto, has been found objectionable in that it caused the forward end of the blank, especially if the blank were soft or spongy, to be "nipped" or disfigured; that is the entering edge of the blank would be crushed or pressed down by the weight of the roller and gear and the knife would momentarily gouge or cut deeper into the blank at the start of the skiving operation than it would after the forward end of the blank had passed the cutting edge of the knife. This objectionable action was presumably due to the weight and inertia of the roller and its gear and was more pronounced when the blank was soft and flexible than when it was harder and more rigid, but in all cases it was apt to occur to some extent.

A principal object of the present invention is to provide means automatically to lift the gauge roller and its gear to permit the forward end of the blank to move into proper position in the skiving mechanism without being subjected to the duty of lifting the roller. The gauge roller 28, 29, which is also a single upper feed roller for propelling the blanks past the knife 13, is lighter than heretofore, the core 28 being constructed of a hollow tubular metal cylinder. The ends of the cylinder 28 are journaled in bearing boxes 30 which slide vertically in ways 31 provided at opposite sides of the frame of the machine, and on one end of the roller shaft, outside of the frame, is fixed a gear 32, which is continuously driven by the usual gear 33, which in turn is continuously driven by the usual gear 34 fast on the main driving shaft 15. On the intermediate part of the hollow cylinder 28 between its ends is secured, by cement or otherwise, a cylindrical cover or sheath 29 of rubber or other yielding resilient material.

Directly beneath the roller 28, 29, and parallel therewith, is a rigid non-rotating supporting bar 35, preferably of hardened steel, providing a smooth surface upon which the blanks slide in their movement against the skiving knife 13 as they are fed forward by the roller 28, 29. The bar 35 is fastened near its ends by means of screws 38 (Figs. 2, 3, and 4) to a block of metal 36 which is, to all intents and purposes, a separately adjustable section or extension of the usual bed plate 37 of the machine. Said extension block 36 is provided with a pair of arms 39 which extend under the main bed plate 37 and are pivotally connected to lugs 37' on the bed plate at 40 so as to swing on a horizontal axis. A pair of springs 62 (Fig. 4) disposed between the block

36 and the end of the main bed 37 yieldingly urge the block away from the bed and hold the arms 39 against the upper ends of the posts 42. These springs are housed in recesses on the inner side of block 36. Near the outer extremity of each arm 39, and upon the under side thereof, is provided a partly spherical socket 41 within which is seated the rounded upper end of a vertical post 42. The lower end of each post is threaded and occupies a threaded aperture in a crossbar 43, which is a rigid part of the machine frame. Fixed to each post 42 is a worm gear 44 engaging a worm 45 fast on a transverse shaft 36^a journaled in bearings on the frame of the machine. One end of shaft 36^a extends outwardly beyond the frame 13 and has fixed thereon a hand wheel 46 (Fig. 2) by means of which it is manually rotated thereby to adjust the posts 42 vertically. Endwise movement of the shaft 36^a is prevented by the hand wheel 46 at one end and a collar 47 fixed to the opposite end.

Near its middle the adjustable extension block 36 is provided with a threaded bore extending therethrough from top to bottom and within this threaded bore is a screw 48 (Figs. 2 and 4) whose upper end abuts against the under side of the bar 35 at a point midway between the two screws 38 and opposite the middle of the roller 28, 29.

As each blank reaches and is engaged by the feed and gauge roller 28, 29, it is slid forwardly 30 on the supporting bar 35 and against the cutting edge of the knife 13 which skives off a slice or shaving of uniform thickness from the underside of the blank, which is the flesh side. The thickness of this skiving may be varied by adjusting the bar 35 toward or away from the knife by means of the hand wheel 46. The adjustable abutments 52 on slide bar 14 have already been adjusted by the detecting means to limit the extent of the movement of separation of the roller 40 28, 29, from the skiving knife, to accord with the thickness of the thinnest spot found by the detecting means. Consequently the roller will at all times maintain the required pressure on the blank to insure proper fleshing. When the roller 45 encounters thicker areas of the blank the resilient cover 29 will yield to permit the blank to pass without affecting the position of the rigid supporting bar 35 or the depth of the skiving.

Since all blanks move along a path substantially in the median line of the machine, the middle part of the bar 35 will be subjected to the greatest wear. To compensate for the wearing down of the middle of the bar 35 and to maintain a true supporting surface over which the blanks slide, the screw 48 may be adjusted to bend or spring the middle of the bar upwardly toward the roller. The screw 48 is fixed in its adjusted position by means of a check nut 49.

The new automatic roller lifting mechanism includes a coiled spring 53 (Figs. 1, 2, 3 and 5) one end of which is connected with a lug on top of the bar 50, and the other end of which is connected to a horizontally and transversely disposed lever 54, fulcrumed at 55 on the frame of the machine. The bar 50 is fixed to the two bearing boxes of the gauge roller 28, 29. The free end of lever 54 rests on one arm of a smaller lever 56 fulcrumed at 57 on the frame of the machine, and the other arm of lever 56 is arranged to cooperate with a cam 58 on a short shaft 59. Shaft 59 carries a gear 60 of the same size as, and meshing with, the gear 24 on cam shaft 25 by which the plunger 26 of the marking wheel is operated.

When the gear 24 is caused to make one revo- 75

lution and stop, as above described, a single rotation is imparted by it to gear 60 and cam 58, and the latter acts through lever 56 to lift lever 54, which in turn acts through spring 53 to lift the gauge and feed roller 28, 29 and its gear 32, until the upward movement of the roller is arrested and limited by the engagement of the wedge-like blocks 51, on the bearing boxes, with the wedge-like abutments 52 on the under side of the slide bar 14. Although the action of the cam 58 and the levers 56 and 54 is positive and constant, the spring 56 constitutes a yielding element in the roller lifting mechanism which permits the roller to be arrested at various elevations according to different adjustments of the abutments 52.

Thus it will be seen that the depression of the trip 21 by the blank as it approaches the skiving mechanism acts both to operate the marking mechanism and to lift the gauge roller of the skiving mechanism before the blank engages the gauge roller so that the forward end of the blank is relieved of this work and the nipping, gouging and deformation of the forward end of the blank are avoided.

It is a desirable feature of the roller lifting mechanism that the lug 61 on bar 50 to which the lower end of the spring 53 is attached is positioned at substantially the center of gravity of the gauge roller 28, 29, and its gear 32 so that the roller tends to move away from the skiving knife substantially equally from end to end without any strong tendency to tilt.

The above described roller lifting mechanism is obviously applicable whether the skiving mechanism is designed for fleshing or for evening.

In Figs. 1 to 4 above described, the skiving mechanism is shown in a form designed for fleshing leather blanks.

Fig. 5 illustrates the roller lifting mechanism applied to an evening mechanism, that is, a skiving mechanism which reduces the blank to a uniform thickness throughout corresponding to the thickness of its thinnest spot, instead of skiving off a cutting of uniform thickness, as is done in fleshing machine, leaving the original variations of thickness in the blank. In Fig. 5 the gauge and feeding roller 28^a has a solid unyielding surface, as is usual in evening machines, and once it has been lifted to the extent limited by the abutments, which have been adjusted to accord with the thinnest spot in the blank, it will not yield farther. The lower blank supporting member is in the form of the usual roller 63, (or it might be in the form of a non-rotating supporting bar 36 as shown in the fleshing machine) and is supported on the usual springs 64. As thicker parts of the blank pass through the skiving mechanism the lower supporting member 63 yields downwardly and causes thicker cuttings to be skived off, thus evening the blank down to a uniform thickness throughout corresponding to the thickness of the thinnest spot. The construction and operation of the roller lifting mechanism applied to the evening mechanism is the same as that described in connection with the fleshing mechanism.

I claim:

1. In a machine of the character described, skiving mechanism including a skiving knife, a vertically movable gauge roller and an adjustable abutment to limit the extent of the movement of separation of the gauge roller from the skiving knife, and mechanism controlled by the

blank during its passage through the machine to lift the gauge roller to the extent permitted by the abutment before the blank engages the gauge roller.

2. In a machine of the character described, skiving mechanism including a skiving knife, a vertically movable gauge roller and an adjustable abutment to limit the extent of the movement of separation of the gauge roller from the skiving knife, and mechanism including a trip in the path of the blanks and actuated by each passing blank to lift the gauge roller to the extent permitted by the abutment before the blank engages the gauge roller.

3. In a machine of the character described, skiving mechanism including a skiving knife, a vertically movable gauge roller and an adjustable abutment to limit the extent of the movement of separation of the gauge roller from the skiving knife, and mechanism controlled by the blank during its passage through the machine to lift the gauge roller to the extent permitted by the abutment before the blank engages the gauge roller, said lifting mechanism including a yielding element adapted to permit the gauge roller to be arrested at various elevations according to different adjustments of the abutment.

4. In a machine of the character described, skiving mechanism including a skiving knife, a vertically movable gauge roller and an adjustable abutment to limit the extent of the movement of separation of the gauge roller from the skiving knife, lifting means to lift the gauge roller to the extent permitted by the abutment before the blank engages the gauge roller, marking means responsive to the detecting means, and a trip in the path of the blanks and actuated by each passing blank adapted to operate both the lifting means and the marking means.

5. In a machine of the character described, skiving mechanism including a gauge feed roller, a skiving knife and a non-rotating supporting bar opposed to the roller and having a smooth surface upon which the blank slides in its movement against the skiving knife, and means to spring the middle of said bar toward the skiving knife to compensate for wear of the bar.

6. In a machine of the character described, skiving mechanism including a gauge feed roller, a skiving knife and a non-rotating supporting bar opposed to the roller and having a smooth surface upon which the blank slides in its movement against the skiving knife, means to adjust the bar toward and from the knife, and means to spring the middle of the bar toward the knife to compensate for wear of the bar.

7. In a machine of the character described, skiving mechanism including a skiving knife, a vertically movable gauge roller and an adjustable abutment to limit the extent of the movement of separation of the gauge roller from the skiving knife, a non-rotating supporting bar opposed to the gauge roller and having a smooth surface upon which the blank slides in its movement against the skiving knife, and means to spring the middle of the bar toward the knife to compensate for wear of the bar.

8. In a machine of the character described, skiving mechanism including a skiving knife, a vertically movable gauge roller and an adjustable abutment to limit the extent of the movement of separation of the gauge roller from the skiving knife, mechanism controlled by the blank during its passage through the machine to lift

the gauge roller to the extent permitted by the abutment before the blank engages the gauge roller, and a non-rotating supporting bar opposed to the gauge roller and having a smooth surface upon which the blank slides in its movement against the skiving knife.

9. In a machine of the character described, skiving mechanism including a skiving knife, a vertically movable gauge roller and adjustable abutment to limit the extent of the movement of separation of the gauge roller from the skiving knife, a rigid supporting member opposed to the gauge roller, said gauge roller having a cylindrical cover of yielding resilient material, and mechanism controlled by the blank during its passage through the machine to lift the gauge

roller to the extent permitted by the abutment before the blank engages the roller.

10. In a machine of the character described, grading means, a vertically movable feed roller for feeding the blanks out of the machine, and mechanism controlled by the blank during its passage through the machine to lift the feed roller before the blank engages the feed roller.

11. In a machine of the character described, grading means, a vertically movable feed roller for feeding the blanks out of the machine, and mechanism including a trip in the path of the blanks and actuated by each passing blank to lift the feed roller before the blank engages the feed roller.

JAMES W. JOHNSTON.
